UNITED STATES PATENT OFFICE.

ARNOLD E. W. JOHNSON, OF CHICAGO, ILLINOIS.

SHOE-SHINING MACHINE.

Application filed March 9, 1922. Serial No. 542,234.

To all whom it may concern:

Be it known that I, ARNOLD E. W. JOHNSON, a citizen of the United States, residing at Chicago, in the county of Cook and State of Illinois, have invented a new and useful Improvement in a Shoe-Shining Machine, of which the following is a specification.

My invention relates to machines for shining shoes and more particularly to a machine that will first clean the shoes, then apply the paste or similar material, and then brush the treated shoes to polish them. These divers steps I accomplish by preferably three batteries or groups of brushes arranged in sets upon suitable carriers and the separate carriers are successively rotated upon a single arbor or in a turret unit.

In carrying out my invention I have numerous objects in view, the principal of which is to provide an automatic machine of this character that is simple in operation so that it requires little or no attention, and which may be readily operated or caused to function by the persons desiring to have their shoes polished. Another object of my invention is to provide in a shoe cleaning and polishing apparatus a novel and effective brush operating mechanism which when in operation will bring the brushes into contact with every portion of the surface of the shoe so as to both thoroughly clean the shoe and polish all portions thereof. The structure I have herein disclosed is for operating upon one shoe at a time, and in this connection I have provided a mechanism controlled by the depositing of a single coin that will thereafter be more or less under the control of the patron so that after one foot has been placed in position the apparatus may be started and will continue operating upon the shoe until the complete cycle has been finished whereupon the machine will stop to permit the patron to remove the foot wearing the polished shoe and position the other foot after which the patron may again start the machine (without depositing another coin) and repeat the cycle of operation upon the unpolished shoe. This permits the patrons to have ample time to change their feet in the machine and liability of the machine or brushes missing or omitting a portion of any cycle of operation is avoided.

A still further object of my invention resides in the provision of brushes and mechanism for rotating and directing them that

will cause them to operate in a yielding manner upon the tops and sides of the shoe under treatment. I have also provided a novel reservoir and dispenser for the polishing paste or other substance used.

Summarized in a general way the objects of my invention reside in the provision of a shoe-shining machine that is novel in construction, dependable in operation, is small and durable in construction, comparatively inexpensive to manufacture so that it may be sold for a moderate price, and which is dependable in performing the functions for which it is designed. All of these objects I prefer to accomplish by the means and in the manner substantially as hereinafter fully described and as more particularly pointed out in the claims, reference being now had to the accompanying drawings that form a portion of this specification and which are in a sense merely diagrammatical for the purposes of illustration. In said drawings, Figure 1 is a longitudinal side elevation of my invention, the carriage being shown in a position where all the brushes of a group are in the act of operating upon a shoe being polished.

Figure 2 is a vertical end elevation of the structure illustrated in Figure 1.

Figure 3 is a top plan of my invention showing the first brushes of a group about to engage a shoe, portions of the mechanism relating to the outer groups of brushes being omitted for the purpose of clearness.

Figure 4 is a plan with a portion of the top platform or cover broken away to disclose the structure beneath the same at the bottom of the mechanism.

Figure 5 is a longitudinal side elevation of a group of brushes and their supporting and actuating mechanism, together with a fragmentary portion of the rotatable turret, the view being enlarged for clearness.

Figure 6 is an end elevation of the structure shown in Figure 5, portions being broken away and in section.

Figure 7 is a detail view of the foot-rest showing the manner of elevating the same for use for low-cut or oxford shoes.

Figure 8 is an enlarged horizontal section of the paste or polish reservoir, illustrating the manner of discharging the contents.

Figure 9 is an end view of said reservoir, parts being broken away and in section to disclose their particular construction.

Figures 10, 11, and 12 are diagrammatic views of a group of brushes illustrating the divers positions assumed by the same in moving past a shoe that is being polished in my machine.

Figure 13 is a top plan of the structure illustrated in enlarged scale in Figures 5 and 6, with portions broken away.

Figure 14 is a horizontal sectional view on line 14—14 of Figure 2 illustrating the manner of discharging polish from the upper or stationary reservoir.

Figure 15 is a similar view on line 15—15 of Figure 2 illustrating the manner of cutting off the discharge of the polish and preventing drip.

Figure 16 is a vertical axial section through the stationary polish can.

In the drawings, which represent a typical embodiment of the preferred form of my invention, I have employed similar reference characters to designate like parts wherever the same appear throughout the several views.

Referring first to Figures 1, 2, 3, and 4, (and particularly Figures 3 and 4) it will be seen I have provided a suitable base 1 of rectangular outline upon which a box-like housing is mounted, said housing consisting of vertical side and end walls 2 and 3 respectively, and a top 4, all of which housing is preferably made of metal plates and encloses the mechanism but which may be lifted off the base 1 so that the mechanism is readily accessible from all sides. The top 4 has an elongated aperture 5 for the insertion of a shoe, the top plate being reinforced around the edges of the aperture with angle metal 6 and having an elevated compartment 7 for certain auxiliary portions of the machine.

Projecting from one of the end walls and extending longitudinally of the housing about centrally thereof is a pair of parallel horizontal sills 8 upon the outer end portions of which the foot-rest plate 9 is mounted. The sills are separated by spacers 10 and are rigidly connected to the end wall by angle piece uprights 11 (Figure 3). Intermediate its ends the sills are supported upon a hanger 12 that is secured to and depends from the horizontal angle-piece 13 connecting the upper ends of uprights 14 that are positioned intermediate the ends of the longitudinal side wall 2.

A pivot bracket 15 secured to and projecting from the hanger 12 has a bell-crank 16 mounted in its outer portion, one arm of said bell-crank being hingedly connected to the adjacent lower end of a vertically disposed reciprocable plunger rod 17 that extends through the upper portion or horizontal member of the hanger 12 and the top 4 in which it is guided and has an operating handle 18 upon its extended end. The

opposite arm of the bell-crank 16 is connected by a link 19 to the lower arm of a lever 20 pivoted intermediate its ends upon the sill 8 and the opposite or upper arm of said lever contacts the under surface of foot-rest plate 9, heretofore mentioned, adjacent the heel portion thereof. The toe portion of the foot-rest plate has a slotted downwardly projecting flange 21 longitudinally disposed with respect to the plate that coacts with a transverse pin 22 on the adjacent portion of the sill 8, and intermediate this flange and the lever 20 is a second lever 23 (similar to lever 20) that has its lower arm connected by a link 24 with the lower arm of lever 20 so as to be operated simultaneously therewith. The upper arm of lever 23 contacts the under surface of the ball portion of the foot-rest plate 9 and when said lever is rocked with lever 20, the foot-plate will be elevated above its normal position, and by making one lever shorter than the other, the foot-rest plate will be tilted in its elevated position, and will be guided and somewhat pivoted by the engagement of the pin 22, with the slot in flange 21. This structure is for the purpose of utilizing the apparatus without other alteration for polishing low cut shoes or oxfords.

Extending longitudinally of the base 1, are parallel tracks 25 and 26, above which are disposed parallel guard rails 27 and 28. Movable on these tracks 25 and 26 is a truck 29 that consists of a suitable platform having depending bearings in which rollers or wheels 30 are journaled that ride on said tracks. The motor 31 for driving the mechanism is mounted at one end of the truck 29 to one side thereof and is provided upon its shaft with a gear 32 that is in mesh with an idle gear 33 journaled on the adjacent portion of a vertical bracket 34 rising from the platform of the truck. Journaled in the upper portion of the bracket 34 is a driven gear 35 mounted upon a drive-shaft 36, revolvably mounted transversely and horizontally in the upper portion of bracket 34. The bracket 34 has horizontally disposed lateral bearing arms 37 and 38 in which are journaled the upper portion of a vertical shaft 39 that carries between the arms 37 and 38 bevel-gears 40 and 41 that are loose upon a shaft 39 and are in mesh with a bevel-drive gear 42 secured upon the adjacent portion of the shaft 36. The movable member or collar 42^a of a clutch mechanism is splined upon shaft 39 between the hubs of the gears 40 and 41 and is moved from one to the other of said hubs by a lever 43 pivoted at one end on the bracket 34 and secured at its free end to a vertically disposed longitudinally movable rod 44. This rod extends down through the platform of the truck 29 and has a roller 45 upon its lower end that is so positioned that

it will engage the underface of the inclined plate 46 located between the tracks adjacent the end of the rearward movement of the truck, so that the clutch member 42^a is shifted from one bevel-gear to the other. An oppositely inclined cam-face 47 at the opposite or forward end of the movement of the truck will move the clutch member to engage the other gear 40. Thus the rotatable shaft 39 is driven in one direction to move the truck rearwardly, and in the opposite direction to move the truck forwardly. The power is transmitted to drive the truck by means of a bevel-gear 48 upon the lower end of the shaft 39 in mesh with a bevel-gear 49 carried upon the outer portion of an internally threaded rotatable sleeve 50. This sleeve is journaled in suitable bearings upon the under side of the truck and a stationary threaded shaft or screw 51 passed therethrough. The ends of the threaded shaft are secured in blocks 52 mounted on the base between the tracks.

A standard 53 rises from the truck adjacent the motor and has a bearing 54 through which the drive-shaft 36 passes and a standard 55 rises from the opposite end of the truck. The upper ends of these standards have bearings to receive a horizontally disposed rod or arbor 56 upon which a turret device is carried as herein-after described. One end of the arbor extends beyond its bearing in standard 53 where it is provided with a circular disk 57 having thereon a plurality, preferably three, lateral detent studs 58 upon which rotatable collars 59 are secured. The arbor 56 is arranged to rotate in bearings so as to bring the sets or groups of brushes into successive operative position with respect to the shoe that is being shined and in order to do this I have provided a vertically positioned reciprocable bar 60 that is guided in brackets 61 on the standard 53, and is kept normally at its lowest position by a contraction spring 62. A lateral finger 63 having a concaved upper surface projects from the top of bar 60, so that its outer end is positioned below the lowermost stud and roller on the disk 57. The lower end of the bar is bifurcated to receive an anti-friction roller 64 that is adapted to engage the inclined cam-face 65 on the base 1, between the tracks and slightly beyond the cam-face 47 heretofore mentioned. When the truck travels to the end of its forward movement, the roller 64 rides up on the cam-face 65 and forces bar 60 upwardly so that the concaved edge of the finger 63 engages the lowermost stud and roller on disk 57 and through the same rotates the arbor 56 a third of a revolution so as to bring the succeeding group of brushes into position in front of the toe of the shoe being shined.

The turret preferably consists of two op-

ositely arranged castings of corresponding shape, each provided with three radially disposed arms 66, 67 and 68. The outer ends of each of these arms connected by cross pieces 69, secured at their ends by nuts or the like, and the ends of the arms are provided with widened extensions 70, each having a notch or recess 71 in its segmental shaped outer edges. Projecting towards the turret, upon the standard 53 is a latch bolt 72 pivoted on a bracket projecting from the standard, and the outer ends of the latch-bolt engages the notch or recess 71 in the turret arms. The opposite end of the latch-bolt extends to adjacent the rod 60 where it is in the path of a lateral lug 73 upon the facing portion of said rod. When the truck is reciprocated and travels to the end of its forward movement to move the rod 60 upwardly, the projection 73 will trip the latch-bolt 72 and release it from the notch or recess 71 in the edge of the turret arm, and it is so timed that this action takes place immediately prior to the engagement of the finger 63 with the stud on the disk 57.

The turret arms 66, 67 and 68, are each provided with a rotatable driving-shaft 74 adjacent to the cross bar 69 which shafts have upon their outer ends a clutch member 75 that is adapted to be engaged by a slideable clutch member 76 mounted upon the adjacent end of the drive-shaft 36. The clutch member 76 is in the form of a sleeve that is reciprocated through the bearing 54 on standard 53 so as to successively engage and operate the shafts 74 on the turret as they are brought opposite thereto. The clutch member 76 is kept normally pressed towards engagement with the clutch member 75 by means of a coil spring 77 that surrounds the drive-shaft 36 and is adapted to be moved out of engagement with its opposing clutch member each time the bar 60 is elevated to rotate the turret. This is done by providing a bell-crank that is pivotally carried upon the outer end of a bracket 78 projecting from the standard 53, one arm 79 of said bell-crank having a roller positioned in the path of a wedge member 80 on the bar 60 so that when the latter is moved upwardly the bell-crank is rocked. The opposite arm 81 of the bell-crank is slotted to receive the transverse pin 82 projecting from a ring 83 fitting into a groove 84 in the adjacent portion of the sleeve of the clutch member 76. It will thus be seen that when the bell-crank is rocked by the cam 80, the arm 81 will slide the sleeve of the clutch member 76, upon the drive-shaft 36, and cause its clutch face to disengage its opposing member 75, on the adjacent end of respective driving-shaft 74.

As seen in the drawings there are preferably three groups of rotatable brushes, each group being supported upon and carried by

one of the arms 66, 67, and 68, of the turret structure, and by rotating the turret as previously described these respective groups of brushes are brought successively into position in front of the shoe being shined, and are rotated through their respective driving-shaft 74, during a reciprocation or backward and forward movement of the truck or carriage 29. The first group to operate upon the shoe is for the purpose of dusting the same, the second group deposit and distribute the polishing paste or other similar material, and the third set of brushes rub the applied polish to finish the polishing operation. The structure of the brushes in the several groups, their manner of operation, and the means for driving the spindles of the brushes in each group are identical. Therefore, for the purpose of convenience but a single group together with its supporting and driving mechanism will be described, it being understood that said description applies equally to each of the remaining groups of brushes mounted upon the turret. A single group of these brushes has been illustrated in an enlarged detail in Figures 5, and 6, of the drawings and will now be described in detail.

A suitable frame, preferably of inverted U-shape, is mounted upon sleeves 85, and 86, projecting from the turret arms 68, and from these sleeves arise the opposite parallel arms 87, and 88 of one frame, which arms are connected at their upper ends by cross piece 89, on which suitable brackets and bearings are provided to receive the spindles and a driving mechanism for the brushes that are to engage one side of the shoe. Spacing collars 90, and 91, loosely surround the sleeves 85, and 86 to separate arms 87, and 88, from the arms 92, and 93 of the other frame which latter arms have a cross piece 94, connecting their outer ends so as to provide a U-shaped frame similar to the other frame formed by arms 87, 88 and cross piece 89. This frame is alongside of, but spaced from said other frame and is provided with brackets and bearings for journaling the spindles of the pair of brushes that are to engage the other half or side of the shoe. These two U-shaped frames have their arms converged towards each other to the sleeves 85, and 86, and have their outer portions pressed yieldingly towards each other so that the brushes in operating upon the shoe will be brought towards each other, or away from each other to conform with the contour of the surface of the shoe, so that all portions of the latter will be engaged by the group of brushes. The converging arms 87, and 92, are respectively engaged by the bowed ends 95, of a coil-spring 96, surrounding the cross rod or tie-piece 69, and the arms 88, and 93, are similarly engaged by the bowed extensions

97, of a coil-spring 98, surrounding the opposite end portion of said cross-piece 69.

A substantially U-shaped yoke 99, has the outer ends of the parallel arms loosely mounted upon shaft 74 adjacent the sleeve 86, and on its cross member is provided with a bearing boss 100, for journaling a transmission-shaft 101 that is provided with a bevel-gear 102, upon its lever end in mesh with a bevel-gear 103 secured upon and rotatable with the driving-shaft 74, so as to actuate the said transmission-shaft whenever the driving-shaft 74 has been operatively connected through the clutch members 75, and 76 with main drive-shaft 36.

A short-shaft 104, disposed laterally to the transmission-shaft 101 is journaled in horizontal bearings 105, and 106, extending from the under side of cross-piece 89, and has bevel-gears 107 and 108 upon its opposite ends. The gear 107 is in mesh with a bevel-gear 109 upon the adjacent portion of transmission-shaft 101, so that the short shaft will be actuated thereby. As noted in Figure 5 of the drawings, the bearing 106 forms a portion of a right angle bracket 110, the ends of which are connected respectively with the cross-piece 89 and the arm 87. In the horizontal portion of this bracket is a bearing 111, to receive the lower end of a substantially vertically disposed spindle 112, that passes upwardly through a bearing 113, alining with bearing 111, and between said bearings has a bevel-gear 114 secured to it that is in mesh with and driven by the bevel-gear 108, on the adjacent end of the short shaft 104. This spindle 112, extends through and beyond the bearing 113, and has a suitable brush 115, secured to it in any suitable manner.

About mid-way the length of cross-piece 89 and arising from its outer surface is a repair of brackets 116 and 117, having bearing bosses 118 and 119 respectively in their outer ends. Another bearing bracket 120, extends outwardly from the end of the cross-piece 89, and spaced from the bracket 116, so that the transmission-shaft 101 extends at its upper end between these brackets and is journaled in a lateral bearing arm 121 projecting from the bracket 116 towards bracket 120. The outer end of bracket 120 has a bearing boss 122, the bore thereof alines with the bore of bearing boss 118, and in the said bore is journaled a stub-shaft 123, having a bevel-gear 124 thereon that is in mesh with and driven by a bevel-gear 125 upon the adjacent portion of transmission shaft 101. The stub-shaft 123 extends beyond the bearing 118 to provide a support and journal for a rocking frame 126 of a hollow rectangular shape that has a stud 127 projecting from its side opposite the stub-shaft 123, so as to be journaled in the bearing boss 119, upon the outer end of bracket 120.

arm 117. As seen in Figure 5, the rocking frame 126 is substantially a square, and the lateral connecting members have bearings 128 and 129, in which portions of a transverse spindle 130 is journaled and which extends beyond bearing 128 to receive a brush 131, that is suitably secured thereto. A bevel-gear 132 on stub-shaft 123, actuates a bevel-gear 133 on spindle 130, to drive the brush 131 and said brush is held yieldingly in an engagement with the surface of the shoe by means of a coil-spring 134, one end thereof being secured to the bracket 117 and the opposite end engaging the rocking frame 126, as will be seen by reference to Figure 5. This structure permits the rocking frame 126 as it passes the shoe during the reciprocation of the truck to move into a vertical plane so that the brush 131 changes its position from a normally horizontal axis when operating upon the forward upper surface of the shoe to a substantially vertical axis when the brush reaches the top and side or rear portion of the shoe, thus conforming itself with the entire contour of the shoe throughout its path of movement. The divers positions assumed by the brushes 115 and 131 in their travel past the shoe are shown diagrammatically in Figures 10, 11, and 12 of the drawings.

The structure upon the U-shaped frame (consisting of the arms 92 and 93, and cross-piece 94) is a substantial counterpart of that carried by the U-shape frame (87—88—89) hereinbefore described, with the exception that the axis of the swiveled brush is staggered with relation to the brush 131, as will be noted in Figures 1, 3 and 5 of the drawings. The frame 92—93—94 extends upwardly from the opposite side of arbor 56 from the frame hereinbefore described as seen in Figures 2 and 6 of the drawings so that the brushes mounted thereon will be in a position to operate upon the surface of the shoe that is not operated upon the brushes on the opposing frame. A yoke has its arms journaled on shaft 74 and gears 103^a and 102^a are mounted respectively upon said shaft and a laterally disposed transmission-shaft 101^a that is journaled at its upper end in the cross-piece 94. A bevel-gear 109^a upon the transmission-shaft drives a bevel-gear 107^a on a short shaft 104^a disposed horizontally and parallel with shaft 104 and having a bevel-gear 108^a upon its end opposite gear 107^a that drives the brush spindle 112^a through the medium gears 108^a and 114^a. The adjacent end of shaft 104^a and the spindle 112^a are journaled in a rectangular bearing frame 110^a in the corner of the frame and upon the upper extended portion of said spindle the vertically disposed brush 115^a is secured. The rocking frame 126^a is journaled between upright brackets

116^a and 117^a, the former being adjacent the arm 93 of the frame and is yieldingly held in position by the spring 134^a. The spindle 103^a of brush 131^a is journaled in this rocking frame and is driven from stub-shaft 123^a by gear connection therewith, said shaft deriving its motion through gears 124^a and 125^a, the latter gear being upon the upper end of transmission-shaft 101^a. As the elements just described are substantially counter-parts of the elements on the opposite frame, the same have only incidentally been mentioned as their construction and operation will be readily understood from the preceding description.

As hereinbefore mentioned the first group of brushes to engage the shoe dust off the surface of the latter and pass to the rear of and beyond the heel of the shoe, Figures 10, 11 and 12 whereupon the reverse movement takes place and the truck again moves past the shoe until the brushes have repeated their dusting operation beyond the toe. The machine then automatically rotates the turret one third of a revolution and brings the polish applying mechanism with its brushes in front of the shoe. In the polish applying group the brushes 115 and 115^a have the polishing paste applied directly to them from a pair of containers or reservoirs which the contents is discharged automatically at preferably three points during the longitudinal movement of the containers past the trip arms 135 and 135^a projecting from opposite side walls 2 of the casing. The polish containers each comprises a box 136 that is closed and has a suitable discharge nozzle 137, and surrounding the paste within the box is a flexible lining or wall 138 secured at one end adjacent one side of the discharge nozzle and at its opposite end portion passed around a roller 139 positioned alongside the opposite edge of the nozzle. After passing partly around roller 139, the flexible wall is secured to an intermittently rotatable winding spool 140, the arbor thereof passes out of the bottom of the box and is provided with a ratchet disk 141. A lever arm is loosely journaled upon the outer end of the spool arbor so that it will be engaged by the trip arms 135 or 135^a hereinbefore mentioned when the polish applying group of brushes is in the uppermost position as shown in Figure 3 of the drawings and the truck moving to the rear. A pawl 143 on the lever arm engages the ratchet disk when the lever arm is moved and thereby rotates the spool 141 to wind upon the latter a portion of the flexible or lining wall 138, thus forcing through the nozzle a portion of the polishing paste and discharges the same upon the brush (115 or 115^a) the periphery of which engages said nozzle.

A quantity of paste is also discharged di-

rectly upon the upper surface of the toe of the shoe through suitable mechanism now to be described so that the tilting brushes 131 and 131^a will, when they come into engagement with the shoe, distribute the same over the upper portion thereof. This mechanism consists of a cylindrical can 144 having a conical discharge bottom 145 and which is mounted upon the top plate 4 inside of the elevated compartment 7. By observing Figures 1, 2 it will be seen the discharge port 146 in the apex of the bottom is positioned above the toe portion of the foot-rest plate 9, so that the paste discharged therefrom will be deposited upon the upper surface of the toe of the shoe when the polish receiving brushes are in their uppermost position. Within the can, upon the upper surface of the paste is a follower-disk 147 that is moved downwardly by a worm or screw 148, journaled in the top of the can and extended through the latter, where it is provided with a ratchet-disk 149 that is intermittently rotated by a pawl 150, pivotally carried by an arm 151, loosely journaled upon the upper end of the worm or screw 148. The outer end of the arm 151 is connected by a link 152 to a lateral arm 153, carried upon the upper end of a vertically disposed rocker-shaft 154, that is journaled in bearing brackets 155, projecting from the adjacent side wall 2. The lower end of the rocker-shaft has a detent 156 projecting laterally or horizontally therefrom into the path of a projection 156^a, carried by the arm 67 of the turret which is disposed upon the adjacent side of the polish applying brushes when the latter are in operative position. The movement of the truck causes the projection 156^a to move the detent 156 which rocks shaft 154, and through the intermediate mechanism rotates the worm or screw 148, which in turn moves the follower-plate 147 a slight distance farther down towards the bottom of the can. This discharges a small quantity of the paste through the discharge nozzle upon the shoe, but as the paste would be in a somewhat ribbon or streamer form, it is necessary to shear this ribbon so that an equal quantity of polish is discharged each time the polish applying brushes are reciprocated in their operating position. This is done by means of a cut-off blade 157, pivoted intermediate its ends upon the bottom of the can and connected at its outer end by a link 158 with a rocker arm 159, secured upon the rock-shaft 154 below the rocker arm 153. The blade is so positioned that one of its ends is moved across the discharge port whenever the shaft 154 is rocked, thus shearing the ribbon of paste at the end of the downward movement of the follower-disk.

Adjacent the can 144, I have provided a suction or exhaust fan 160 having its inlet

nozzle 161 positioned in front of the shoe, so that the dust and other matter removed from the shoe will be drawn out of the casting or box enclosing the mechanism when the dusting brushes are operating. The fan 70 is controlled through a switch 162, from which a rocker-arm 163 projects into the path of a finger 164, projecting from the arm 67 of the turret so that the fan is in operation only when the dusting and cleaning group of brushes is operating. When the truck starts to move rearwardly with the dusting brushes uppermost, the finger 164 will swing the rocker-arm 163 to open the switch and start the fan in the blower and when the truck approaches the end of its return movement the rocker-arm 163 is moved in the reversed direction to close the circuit and stop the fan.

The cycle of operation of the mechanism hereinbefore described is substantially as follows it being understood that the movement of the truck in a direction from the toe of the shoe towards the heel is rearwardly and opposite direction of movement is forwardly:—The shoe is placed upon the foot-rest plate 9, with the dusting group of brushes in front of the toe, and the motor started by depressing the rod 173 (hereinafter described). The shaft 36 is clutched 95 with the driving-shaft 74 on the arm 68 of the turret and through the transmission-shafts 101 and 101^a rapidly rotates the two pairs of the brushes carried upon the U-shaped frames. The worm sleeve 50 through the shaft 39 moves the truck 29 to the rear until all the brushes have operated and passed beyond the heel of the shoe. The shifting-rod 44 thereupon engages its cam-face 46 which reverses the direction of rotation of shaft 39 and the worm sleeve 50 drives the truck in the opposite direction until the rotating brushes have moved in front of and past the toe of the shoe. As soon as the dusting brushes have moved out of contact of shoe the clutch members 75, and 76 are disengaged by the reciprocating vertical rod 60 engaging its cam 65 and at the same time the latch-bolt 72 is released from the notch 71 in the turret arm and the pawl 58 and finger 63 has engaged the lowermost stud 58 and pushed it upward so as to rotate the turret, which is now released, one-third of a revolution upon its arbor 56. Upon the lowering of the rod 60 the latch-bolt 72 enters the notch in a next turret arm 67 and the clutch member 76 has engaged the clutch member 75 upon the end of the shaft 74 which has just been brought into alinement therewith. This will bring the polish applying brushes in front of the toe of the shoe and when the direction of rotation of shaft 39 has been reversed by the bar 44 engaging the front cam-face 47, the truck 29 will immediately begin to move towards the rear 130

again. This movement will cause a discharge of paste from the can 144 upon the top of the shoe and the boxes 136 will discharge polish upon the brushes 115 and 115^a. Upon reaching the limit of its rearward movement the truck is reversed in the manner heretofore described and begins its forward movement, so that the polish applying brushes will evenly distribute the paste upon all portions of the surface of the shoe. Upon reaching the limit of its forward movement, the clutch members 75 and 76 are again released, together with the latch-bolt 72 and the turret will again move a third of a revolution to bring the finishing brushes into their proper position in front of the toe of the shoe. The finishing operation is a repetition of the operation by the dusting brushes and therefore need not be described in detail. As soon as the finishing operation has been completed, the motor is switched off so that none of the mechanism is in operation while the person is removing the polished shoe and placing the other shoe properly upon the foot-rest plate 9. The mechanism for carrying out this function comprises an intermittently moved rock-shaft 165 journaled in a standard 166 arising from the base 1 and carrying upon its outer end a detent 167 to be engaged by a projection 168 on the truck 29. A pawl 169 is carried by said shaft 165 and engages a ratchet 170 mounted upon the spindle 171 of a rotatable switch element 172. The rock-shaft 165 is rotated a fourth of a revolution by each reciprocation of the truck so that the circuit is opened through the switch 172 while the spindle is being rotated all but a portion of a revolution. The last reciprocation of the truck will move the contacting members of the switch out of engagement to break the circuit, which takes place when the finishing brushes have completed their operation. The motor has now been stopped and the polished shoe removed and the other placed on the foot-rest whereupon the operator depresses the plunger rod 173 which rotates the switch mechanism a quarter turn and moves the contact elements thereof again into engagement with each other to make the circuit and start the motor.

In connection with my hereinbefore described mechanism I prefer to employ a suitable coin controlled device for latching and releasing the plunger-rod 173, so that the apparatus may be installed in divers locations, and operated by the customer upon depositing a coin, so that an operator or attendant is not necessary. Such coin controlled mechanism forms no part of my present invention and any device suitable for locking the plunger-rod when not in use and for keeping it released while both shoes are being shined may be employed. It will

be apparent to others skilled in the art, that divers modifications may be made to the precise construction herein shown and described, and such changes may be made without departing from the principles I have employed. I therefore, desire it understood that such changes and modifications are fully contemplated as coming within the scope of the appended claims.

What I claim is:

1. A shoe shining machine comprising an arbor, a rotatable turret mounted thereon having a plurality of radially disposed members, frames pivotally carried by said radial members, spindles extended from said frames upon which suitable brushes are mounted, and rocking-frames pivoted on said first frames upon which suitable brushes are mounted with their axes normally transverse to the axes of the first-mentioned brushes.

2. A shoe shining machine comprising an arbor, a rotatable turret mounted thereon having a plurality of radially disposed members, frames pivotally carried by said radial members, spindles extended from said frames upon which suitable brushes are mounted, rocking-frames pivoted on said first frames upon which suitable brushes are mounted with their axes normally transverse to the axes of the first-mentioned brushes, and a reciprocable carriage upon which said structure is mounted whereby said brushes are moved bodily past the article upon which they are operating.

3. A shoe shining machine comprising an arbor, a rotatable turret mounted thereon having a plurality of radially disposed members, frames pivotally carried by said radial members, spindles extended from said frames upon which suitable brushes are mounted, and rocking-frames pivoted on said first frames upon which suitable brushes are mounted with their axes normally transverse to the axes of the first-mentioned brushes, and means for intermittently rotating said turret upon said arbor whereby the groups of brushes carried by said frames are moved successively into position relative to the article being operated upon.

4. A shoe shining machine comprising an arbor, a rotatable turret mounted thereon having a plurality of radially disposed members, frames pivotally carried by said radial members, spindles extended from said frames upon which suitable brushes are mounted, rocking-frames pivoted on said first frames upon which suitable brushes are mounted with their axes normally transverse to the axes of the first-mentioned brushes, a reciprocable carriage upon which said structure is mounted, means operated at the end of a reciprocation of said carriage to rotate said turret a predetermined dis-

- tance, whereby the respective groups of brushes are successively brought into operative position.
5. In a shoe shining machine a foot-rest, a rotatable turret bodily reciprocable past said foot-rest in both directions a plurality of brushes arranged in groups upon said turret each group adapted to be brought into co-active position relative to said foot-rest, driving means adapted to successively actuate the groups of brushes, and means for rotating said turret after a group of brushes has operated at and moved past said foot-rest.
- 10 6. In a shoe shining machine a foot-rest, a rotatable turret bodily reciprocable past said foot-rest in both directions a plurality of brushes arranged in groups upon said turret each group adapted to be brought into co-active position relative to said foot-rest, driving means adapted to successively actuate the groups of brushes, means for rotating said turret after a group of brushes has operated at and moved past said foot-rest, a polish reservoir having a valve-controlled normally closed discharge orifice, and means for opening said orifice to discharge polish upon a predetermined group of brushes.
- 15 7. A shoe shining machine comprising a reciprocable support, frame-arms pivotally carried thereby, substantially vertically disposed brushes mounted on said frame-arms, rocking frames pivoted on said frame-arms, and brushes mounted on said rocking frames with their axes normally transverse to the axes of the first-mentioned brushes.
- 20 8. In a shoe shining machine a reciprocable support a pair of frame-arms pivotally journaled on said support, means for yieldingly corelating said frame-arms, spindles mounted upon the outer portions of said frame-arms, rotatable brushes journaled on said spindles, yieldable rocking frames pivotally carried by said frame-arms adjacent said spindles, and oppositely arranged rotatable brushes mounted on said rocking frames with their axes normally transverse to the axes of the first-mentioned brushes.
- 25 9. In a shoe shining machine a reciprocable carriage a horizontal rod supported thereon, a pair of frames pivotally mounted on said rod, said frames comprising inverted substantially U-shaped structures the parallel arms thereof being journaled at their outer ends on said rod and the connecting portions of said U-shaped structure provided with suitable bearings, rotatable spindles journaled in said bearings and having brushes mounted thereon, a drive-shaft and means operatively connecting said shaft and said spindles whereby said brushes are rotated, and devices for yieldingly maintaining said frames normally pressed towards each other.
- 30 10. In a shoe shining machine a reciprocable carriage a horizontal rod supported thereon, a pair of frames pivotally mounted on said rod, said frames comprising inverted substantially U-shaped structures the parallel arms thereof being journaled at their outer ends on said rod and the connecting portions of said U-shaped structure provided with suitable bearings, rotatable spindles journaled in said bearings and having brushes mounted thereon, a drive-shaft, a driven-shaft actuated thereby, a transmission-shaft for each frame and geared to said driven-shaft, and rotatable means connecting said transmission-shafts and the respective spindles.
- 35 11. In a shoe shining machine a reciprocable carriage a horizontal rod supported thereon, a pair of frames pivotally mounted on said rod, said frames comprising inverted substantially U-shaped structures the parallel arms thereof being journaled at their outer ends on said rod and the connecting portions of said U-shaped structure provided with suitable bearings, rotatable spindles journaled in said bearings and having brushes mounted thereon, a drive-shaft, a driven-shaft actuated thereby, a transmission-shaft for each frame and geared to said driven-shaft, and rotatable means connecting said transmission-shafts and the respective spindles.
- 40 12. In a shoe-shining machine, a reciprocable carriage, a pair of frames pivotally mounted thereon, and yieldingly pressed towards each other, a rotatable brush on each frame having fixed bearings, and a rotatable brush on each frame having a tilttable bearing whereby the same are moved independent of the movement of the respective frames in an arc while rotating in engagement with a shoe.
- 45 13. In a shoe-shining machine, a reciprocable carriage, a pair of frames pivotally mounted thereon, and yieldingly pressed towards each other, a rotatable brush on each frame having fixed bearings, rocking frames journaled on said pivoted frames, and rotatable brushes journaled in said rocking frames whereby said brushes are moved independent of the movement of the respective frames in an arcuate path while rotating in engagement with a shoe.
- 50 14. In a shoe-shining machine a suitable support, a pair of frames mounted thereon, and movable towards and away from each other, rotatable brushes having fixed vertical bearings in said frames, tilttable devices on said frames, and rotatable brushes journaled on said tilttable devices, whereby said brushes will cause said devices to tilt independent of the movement of the respective frames during the engagement of the brushes with a shoe.
- 55 15. In a shoe-shining machine a suitable support, a pair of frames mounted thereon and movable towards and away from each

other, rotatable brushes having fixed vertical bearings in said frames, tilttable devices on said frames, brushes mounted on said tilttable devices, a transmission-shaft for each frame, a common drive-shaft actuating said transmission-shaft, and stub-shafts operatively connecting each transmission-shaft with the brushes upon its respective frame.

16. In a shoe-shining machine a suitable support, a pair of frames mounted thereon and movable towards and away from each other, rotatable brushes having fixed vertical bearings in said frames, tilttable devices on said frames, brushes mounted on said tilttable devices, a drive-shaft, a transmission-shaft for each frame and geared to said drive-shaft, stub-shafts for the spindles of the first-named brushes and geared to their respective transmission-shafts, and 20 stub-shafts for the spindles of said tilttable brushes and geared to their respective transmission-shafts.

17. A shoe-shining machine comprising a reciprocable carriage, a turret journaled thereon, means actuated by the reciprocation of said carriage for intermittently rotating said turret, brushes arranged in groups on said turret, driving-shafts journaled on said turret and corresponding in number to the 25 brush groups, a motor-shaft, means for connecting said motor-shaft with the respective driving-shafts as they are successively brought into alinement with said motor-shaft, and transmission-shafts operatively 30 connected to their respective driving-shafts, and their respective group of brushes.

18. A shoe-shining machine comprising a reciprocable carriage, a turret journaled thereon, means actuated by the movement 40 of said carriage for intermittently rotating said turret, a plurality of frames arranged in pairs and the pairs disposed equidistant around said turret, rotatable brushes journaled on said frames, and devices for actuating said brushes in groups 45 consisting of a driving-shaft for each pair of frames, a transmission-shaft movable with each frame, and lateral shafts geared to said transmission-shafts, and the spindles 50 of said brushes.

19. In a shoe-shining machine two groups of rotatable brush spindles, said groups being normally urged towards each other, and means permitting certain of said spindles to be bodily moved with respect to the other spindles whereby the brushes thereon independent of the movement of the respective frames may be moved from normally horizontal to substantially vertical positions while engaging a shoe. 65

20. In a shoe-shining machine pairs of frames pivoted at one end, means for maintaining the free ends of said frames yieldingly in a predetermined position, brushes journaled in said frames, journal-frames 65 pivotally mounted and yieldingly maintained in said frames in a predetermined position, brushes mounted in said journal-frames normally at right angles to said first-mentioned brushes, and instrumentalities for rotating said respective brushes from a common source of power. 70

21. In a shoe-shining machine a normally horizontal foot-rest plate, and means for tilting said plate upwardly from the toe 75 portion thereof and simultaneously elevating the plate from end to end.

22. In a shoe-shining machine, a reciprocable carriage, a pair of frames pivotally mounted thereon, and yieldingly pressed 80 towards each other, tilttable devices upon said frames, and a normally horizontal rotatable brush on each device whereby the same is moved independent of the movement of the respective frames in an arc 85 while rotating in engagement with a shoe.

23. In a shoe-shining machine a suitable support, a pair of frames mounted thereon and movable towards and away from each other, tilttable devices on said frames, 90 and normally horizontal rotatable brushes journaled on said tilttable devices whereby said brushes will cause said devices to tilt independent of the movement of the respective frames during the engagement of the 95 brushes with a shoe.

Signed at Chicago, county of Cook, and State of Illinois, this 6th day of March, 1922.

ARNOLD E. W. JOHNSON.
